E. J. DENISON

FILM REEL

Filed March 29, 1922

Inventor
Carl J. Denison

By his Attorney
Maurice Block

UNITED STATES PATENT OFFICE.

EARL J. DENISON, OF NEW YORK, N. Y.

FILM REEL.

Application filed March 29, 1922. Serial No. 547,822.

To all whom it may concern:

Be it known that I, EARL J. DENISON, a resident of New York city, county and State of New York, and a citizen of the United States of America, have invented certain new and useful Improvements in Film Reels, of which the following is a specification.

This invention relates to improvements in 10 reels for motion picture films, one of the objects being to provide a reel that can be taken apart for shipment or storage in order that the side disks, forming part of the reel, can be shipped flat or stored away flat, 15 whereby a great saving of space is effected. A further object of the invention is to provide an improved form of clip to secure the end of a film to the hub of the reel.

I will now proceed to describe my invention in detail, the novel features of which I 20 will finally claim, reference being had to the accompanying drawing, wherein:—

Fig. 1 is a sectional view of my improved reel, the section being taken on line 1—1 in 25 Fig. 2;

Fig. 2 is a side elevation of the reel looking from the right in Fig. 1;

Fig. 3 is a perspective detail view of the separator;

30 Fig. 4 is a similar view of the clip; and

Fig. 5 is a detail side view of the hub core of the reel.

As herein constructed, my improved reel comprises disk-members 6 and 7 spaced apart 35 to receive therebetween a film, and a hub member indicated generally by 8. The hub member 8 is made up of a core member consisting of head-members 9 and 10 connected by a spindle 11; as a matter of fact, the heads 9 and 10 are carried by the spindle at 40 its ends. In this instance, head 9 carries an annular shoulder 12 at its outer end, and head member 10 carries a threaded projection 13 of smaller diameter. The head 9 45 engages an opening 6^a in disk 6 and head 10 an opening 7^a in disk 7. The disks 6 and 7 are maintained in spaced relationship by a separator or sleeve 14 which fits over heads 9 and 10, said sleeve being provided with a 50 slot or groove 15 in the bore thereof. The threaded projection 13 is engaged by a nut 16 which, when screwed home, tightly binds the disks 6 and 7, the disk 6 being held between shoulder 12 on head 9, and the adjacent end of sleeve 14, the disk 7 being held 55 between nut 16 and adjacent end of sleeve 7.

To fasten a film to the hub 8, I provide a clip 17 of channel or U-shaped formation to engage one end of sleeve 14, or rather to be held by sleeve 14 at one end thereof, as 60 indicated in Fig. 1. The shorter leg 18 of clip 17 fits within slot 15 in sleeve 14, while the longer yieldable leg 19 lies upon the outer surface of sleeve 13. The film to be fastened to the hub 8 will be flexed and 65 passed under clip 17, as indicated by dotted lines 20, Fig. 1.

Should it be desirable to store the reel or 70 ship same in quantities, the nut 13 will be removed, after which the reel members can be taken apart. After the reels have been 75 taken apart, the disks 6 and 7 can be piled up one upon the other. The disk 6 can be slipped off over head 10 and likewise slipped on over head 10.

What I desire to secure by Letters Patent is:—

1. In a film-reel, a hub member, disks carried thereby, means to removably retain the disks in position upon the hub, a sleeve associated with said hub member, said sleeve being provided with an interior channel, and a clip disposed in said channel and having one end in resilient engagement with the exterior of said sleeve. 80

2. A hub member for a film-reel, a core, a shoulder at one end of the core and a threaded projection at the other end of the core to receive a nut member, a spacing sleeve to fit over the core, all arranged to retain a disk between the shoulder and sleeve at one end of the hub, and another disk between the nut member and sleeve at the other end of the hub, and a clip carried by the sleeve having one of its ends located between the 90 sleeve and core member of the hub. 95

3. A hub member for a film-reel, a core, a shoulder at one end of the core and a threaded projection at the other end of the core to receive a nut member, a spacing sleeve to fit over the core, all arranged to retain a disk between the shoulder and sleeve at one end of the hub, and another disk between the nut member and sleeve at the other end of the hub, said sleeve having a slot interiorly 100 thereof, a channel shaped clip having one end inserted in said slot and located between the sleeve and core member of the hub, the other end of the clip being located on the exterior surface of the sleeve. 105

EARL J. DENISON.
